UNITED STATES PATENT OFFICE.

CARL VOORHEES, OF FLORA, INDIANA.

DESIGN FOR A TOY COASTER.

58,170.

Specification for Design. Patented June 14, 1921.

Application filed March 12, 1921. Serial No. 451,818. Term of patent 7 years.

To all whom it may concern:

Be it known that I, CARL VOORHEES, a citizen of the United States, residing in the town of Flora, county of Carroll, and State of Indiana, have invented a new, original, and ornamental Design for a Toy Coaster, of which the following is a specification, reference being had to the accompanying drawing, forming a part thereof.

The ornamental design for a toy coaster as shown.

In witness whereof I have hereunto affixed my signature.

CARL VOORHEES.
